UNITED STATES PATENT OFFICE.

EDWIN F. GUTH, OF ST. LOUIS, MISSOURI.

LIGHTING FIXTURE.

Application filed July 13, 1925. Serial No. 43,092.

My invention relates to that class of units which are enclosed, so as to eliminate the collection of dust, dirt, bugs, etc., on the bottom of the globe, and yet to produce an efficient unit which will be highly brilliant, without any glare.

My invention consists of certain details of construction hereinafter set forth and illustrated in the accompanying drawings, 10 in which

Fig. 1 is a side elevation of my improved lighting fixture having a portion of the reflecting surface of the canopy broken away to show the interior construction;

15 Fig. 2 is a detail view of the mounting for holding the globe in position.

Similar reference numerals refer to similar parts throughout the entire description.

As shown in the drawings, my improved 20 lighting fixture unit may be suspended from a chain 1, and attached to the ceiling canopy 2, in the usual manner. At the lower end of the chain 1 is mounted a holder 3 of standard construction. To this holder, I secure 25 an enclosed globe 4. This globe is constructed, as clearly seen in the drawings, of two parallel ribs 5 and 6, which are connected together by downwardly and inwardly tapering side walls 7. The bottom 30 is closed by convex member 8 and the top is formed by an inwardly extended truncated conoidal portion 9. The reflector canopy 10 is provided with a substantially horizontal reflecting surface 11, in the central portion of which an opening 12 is formed, which permits the upper portion 35 of the truncated conoidal portion 9 of the globe to project through, to permit the light rays to illuminate the ceiling, though it may be located just below the reflector.

The reflector is held in position by means of three straps 13 which are properly located equidistant from each other, and are secured to the holder 3, so as to suspend the 45 canopy 10 therefrom, without letting its weight rest upon the glass globe.

The globe 4 which is preferably formed of translucent glass does not interfere with the efficiency of the unit as a light giver but

does entirely minimize the glare which 50 would be present if the lamp were not shielded by some such globe or shield. It will also be obvious from an inspection of the drawings, that the globe 4 is completely 55 enclosed so that there is no danger whatever of dust, dirt, bugs, etc. getting inside and interfering with the efficiency of the unit.

By tapering the side walls, in the manner in which I do, a large number of the light rays are deflected and redirected to the surface of the reflecting surface of the canopy reflector, thus utilizing a large number of these rays which would otherwise be lost on the ceiling. At the same time, by permitting a small portion of the truncated conoidal part of the globe to extend through the canopy, it will, as indicated by the lines in the drawing, throw sufficient direct light 60 above the canopy reflector to effectually remove all sense of gloom or darkness above 70 the unit, and yet does not sacrifice enough of the reflecting surface to materially interfere with the efficiency of the unit as a 75 whole.

Having thus described my invention what 75 I claim and desire to secure by Letters Patent of the United States is:

1. A lighting fixture, comprising a hanger, an enclosed cylindrical globe having parallel ribs at the top and bottom, and downwardly 80 and inwardly tapering side walls, and an inwardly extending truncated conoidal portion which extends from the upper rib to the hanger, a canopy reflector, having a substantially horizontal reflecting surface which 85 reflects the light rays to the working plane, there being a central opening in said reflector through which said conoidal portion extends, to illuminate the ceiling.

2. A lighting fixture, comprising a hanger, 90 an enclosed cylindrical globe having parallel ribs at the top and bottom, and downwardly and inwardly tapering side walls, and an inwardly extending truncated conoidal portion which extends from the upper rib to 95 the hanger, a canopy reflector, having a substantially horizontal reflecting surface which reflects the light rays to the working plane,

there being a central opening in said reflector to permit the light rays from the truncated conoidal portion to illuminate the ceiling.

3. The combination with a canopy, having a substantially horizontal reflecting surface of an enclosed globe, the sides of which

taper downwardly, the upper part of which comprises an inwardly extending truncated conoidal portion, there being an opening in ¹⁰ the central part of said canopy through which the light rays from the conoidal portion may illuminate the ceiling.

EDWIN F. GUTH.
